END STANDARD FOR A SOFA OR THE LIKE

Edward William Harman, Newton, N.C., assignor to Dresden Lounge Co. Inc., Maiden, N.C., a corporation of North Carolina

Filed May 15, 1969, Ser. No. 17,155

Term of patent 14 years

Int. Cl. D6—01

U.S. Cl. D15—8

FIG. 3.

FIG. 1.

FIG. 2.

FIG. 1 is a perspective view of an end standard for a sofa or the like showing my design.

FIG. 2 is a perspective view of the opposite face thereof.

FIG. 3 is a cross-sectional view enlarged taken along line 3—3 in FIG. 1.

I claim:

The ornamental design for an end standard for a sofa or the like, as shown.
